SET OF EDUCATIONAL TOY BLOCKS

Ruth S. Claffin, Park Ridge, Ill.

Application June 9, 1949, Serial No. 3,134

Term of patent 7 years

(Cl. D34—15)

To all whom it may concern:

Be it known that I, Ruth S. Claffin, a citizen of the United States, residing at Park Ridge, in the county of Cook and State of Illinois, have invented a new, original, and ornamental Design for a Set of Educational Toy Blocks, of which the following is a specification, reference being had to the accompanying drawing, forming a part thereof, in which:

Fig. 1 is a perspective view of one of the blocks in the set of educational toy blocks, showing my new design;

Figs. 2 to 7, inclusive, are plan views of the six faces on the block shown in Fig. 1;

Fig. 8 is a perspective view of another of the blocks in the set of educational toy blocks;

Figs. 9 to 14, inclusive, are plan views of the six faces on the block shown in Fig. 8;

Fig. 15 is a perspective view of another of the blocks in the set of educational toy blocks;

Figs. 16 to 21, inclusive, are face views of the six faces on the block shown in Fig. 15.

I claim:

The ornamental design for a set of educational toy blocks, substantially as shown.

RUTH S. CLAFFIN.
